UNITED STATES PATENT OFFICE.

IRL R. HICKS, OF HALLSVILLE, MISSOURI.

PRIMING SPARK-PLUG.

1,152,177.

Specification of Letters Patent. Patented Aug. 31, 1915.

Application filed April 17, 1914. Serial No. 832,611.

To all whom it may concern:

Be it known that I, IRL R. HICKS, a citizen of the United States, residing at Hallsville, in the county of Boone and State of Missouri, have invented certain new and useful Improvements in Priming Spark-Plugs, of which the following is a specification.

This invention relates to spark plugs for internal combustion engines and more particularly to a combined spark plug and priming device for feeding liquid fuel directly to the combustion chamber of the engine.

An object of the invention is the provision of a hollow central electrode for conducting the liquid fuel to the spark gap of the plug.

Another object is the provision of a novel type of needle valve adapted to coöperate with the end of the hollow electrode to close the opening through the latter and constituting, when in closed position, a lock insuring against loosening of the terminal engaging nuts of the plug.

With these and other objects in view, the invention consists in the novel construction, arrangement and combination of parts as will be hereinafter specifically described, claimed and illustrated in the accompanying drawings, in which the figure represents a longitudinal central sectional view through a spark plug constructed in accordance with my invention.

Referring to the drawing in detail, wherein similar reference numerals designate corresponding parts throughout the several views, the numeral 5 indicates a fragment of a cylinder of the internal combustion engine type having a threaded opening 6 therethrough for receiving the threaded end 7 of the hollow body 8 of a spark plug of ordinary construction. The outer end of the body 8 is preferably formed with a hexagonal nut whereby the plug may be quickly and conveniently removed by the application thereto of a suitable wrench. A core 9 formed of porcelain or other insulating material is provided with an annular enlargement 10 adapted to engage the shoulder

formed internally and centrally of the body of the plug. A threaded sleeve 11 is positioned within the body 8 and is engaged against the annular enlargement 10 to lock the porcelain core 9 against removal. An electrode 12 is secured to the threaded end of the body and is curved inwardly toward the center thereof. 50

The central electrode 13 of the plug is secured centrally within the porcelain core 9 by a nut 14 or other suitable means positioned over the threaded outer end of the electrode 13. A central opening 15 extending from end to end of the electrode 13 is flared at one end as indicated at 16 and the opposite end communicates with a threaded opening receiving the threaded end 17 of 60 the point 18 normally spaced from the electrode 12 to provide a spark gap 19. A nut 20 is threaded on the end of the electrode 13 and adapted to coöperate with the nut 14 to secure the electrical connection for the center electrode 13 in position. 65

A priming cup 21 is formed integrally with the nut 20 and communicates with the threaded bore through said nut. A needle valve 22 is positioned in the threaded opening of the cup and the pointed end 23 thereof is adapted to be seated in the flared end 16 of the opening 15 to close communication through the latter. The valve 22 is formed with a longitudinal groove 24 adapted to 70 permit gasoline or other liquid fuel to flow from the priming cup 21 into the hollow electrode 13 when the valve 22 is open. A suitable head 25 is preferably formed on the closed end of the valve 22 whereby the same 75 may be conveniently manipulated.

What I claim is:

A spark plug including a body, a central electrode secured in said body projecting outwardly of the inner and outer ends of the latter having external screw-threads and a longitudinal opening therethrough, a nut threaded on the outer exposed end of said electrode of greater length than said exposed end, a priming cup formed integral 80 with said nut and communicating with the

threaded bore thereof, a screw-threaded needle valve fitted in said nut having a longitudinal groove and adapted to coöperate with the outer extremity of said central electrode to close the longitudinal opening in the latter, and a head carried by the outer extremity of said valve.

In testimony whereof I affix my signature in presence of two witnesses.

IRL R. HICKS.
